UNITED STATES PATENT OFFICE.

HELENE L. SWEENEY, OF BOSTON, MASSACHUSETTS.

PORTIÈRE-HOLDER.

1,238,214.

Specification of Letters Patent. Patented Aug. 28, 1917.

Application filed June 1, 1917. Serial No. 172,289.

To all whom it may concern:

Be it known that I, HELENE L. SWEENEY, a citizen of the United States, residing at Boston, county of Suffolk, State of Massachusetts, have invented an Improvement in Portière-Holders, of which the following description, in connection with the accompanying drawing, is a specification, like characters on the drawing representing like parts.

This invention relates to a device for supporting a portière, curtain or similar article wherein the upper edge is to be held elevated or supported above the point at which the portière, curtain or similar article as a whole is supported. The device is particularly adapted for application to what is known as a "French plaited heading" portière wherein the body of the portière is formed into a series of groups of vertical plaits which project from the face of the portière and are stitched together at the back. It is the practice so to support this style of portière that the upper edge extends above and conceals the rod and ring or other suitable support by which the portière is supported.

The object of the invention is to provide a device which is self-attachable to the portière, curtain or other article and which therefore requires no sewing or fastening to hold it in place.

The object of the invention is to provide a device of this character which shall be entirely invisible at the face of the portière and which at the back of the portière shall only protrude sufficiently to enable it to perform its function.

The object of the invention is to provide a device of this character which shall be formed from a single piece of wire and which thus may be simply and economically manufactured.

These and other objects of the invention will appear more fully in the accompanying description and drawings and will be particularly pointed out in the claims.

The drawings show the invention in its preferred forms for supporting a portière of the "French heading" type on an ordinary rod provided with curtain rings.

In the drawings,

Figure 1 is a perspective showing the portion of the back of a French plaited portière with a preferred form of device embodying the invention in place therein;

Fig. 2 is a view in side elevation partially in cross section showing an ordinary curtain rod, curtain ring, another form of device embodying this invention with the portière indicated in dotted line;

Fig. 3 is a view in rear elevation of the form of device embodying this invention shown in Fig. 1;

Fig. 4 is a view in side elevation of the device shown in Fig. 3;

Fig. 5 is a view in cross section taken on the line 5—5 of Fig. 3.

The device or portière holder of this invention in its preferred form as illustrated is formed from a suitable piece of wire, the size and flexibility of which is determined by the weight of the portière, curtain or article to be supported, and the length of the upper edge which is to project above the actual point of support. The device should be of sufficient strength to maintain its shape under ordinary conditions of use and of sufficient flexibility to enable it to be bent into the required shape.

The device presents a body or frame portion, an upstanding hook adapted to receive and hang to a suitable supporting device such as the ordinary curtain ring, and an upstanding arm provided well above said hook with a vertical prong adapted to catch and support the upper edge of the portière. In the preferred forms illustrated the device is made of a single piece of wire, a portion of which is bent to form the body or plane and the ends of which are bent to form respectively the upstanding arm and the upstanding hook.

In the construction illustrated in Figs. 1, 3, 4 and 5, the wire is bent to form the thin, flat skeleton frame portion 1, which when in position extends horizontally and acts to support the weight of the body of the portière. The shorter of the two ends of the wire is bent upwardly from the center of this frame portion to form the upstanding hook 2. This hook is preferably bent at its shank 3 in a flat vertical curve opposite to the projecting point 4 of the hook, and the center of the hook loop is placed vertically above the frame. The longer of the two ends of the wire is bent upwardly from this plane portion into the form of an arm extending up parallel with and slightly separated from the hook 2. This arm 5 at a point well above the hook 2 is provided with a preferably vertically arranged prong

6. This prong is permanently located directly above the axis of suspension of the hook 2, and is provided with a point.

The manner of use of the device described will be understood by reference to Fig. 1. In this figure the upper portion of a French plaited portière is illustrated. The material 7 of which the portière is made is formed into a series of groups of vertical plaits one 10 such group of four plaits 8 being illustrated. These plaits project from the face of the portière and are stitched together at the back as indicated at 9. In applying the portière holder the upstanding hook 2 is pushed 15 in between the folds and behind or underneath the stitching 9, the curve 3 of the shank assisting the operation. When the hook is in place the pointed end 4 projects from the back of the portière in position to 20 receive a suitable supporting device such as an ordinary curtain ring while the weight of the body of the portière is taken mainly by the frame 1. The upstanding arm 5 is left on the exterior surface of the back of 25 the portière and the device is so positioned that the upper end of this arm provided with the prong 6 comes near the upper edge of the portière. The prong is then caught in the material of the portière near the upper 30 edge and the arm thus acts to support and hold elevated the upper edge portion of the portière and cause the upper edge portion to conceal the usual suspending devices such as the rod and ring.

35 As many of the holders are used as is necessary properly to support the portière. It will be observed that the holder is inserted and retained in place without sewing or fastening and simply by pushing the hook into 40 the material of the portière and in the case of the French plaited portière preferably between the plaits and behind or beneath the stitching already in place and by which the plaits of the portière are held together.

45 Another form of the invention is illustrated in Fig. 2. This device is also preferably made of a single piece of wire and presents the frame portion 10 with the upstanding hook 11 bent and shaped as in the 50 construction already described. In this second form, however, the upstanding arm 12 is bent outwardly, upwardly and rearwardly so that it may extend around the opposite side of the usual curtain rod 13 from which 55 the portière itself, herein illustrated in dot-

ted lines at 14, extends. The arm is provided with the prong 15 which is adapted to catch into and support the upper edge of the portière. This device is inserted into and held in place in the portière in the same 60 manner as that already described.

In both forms the upstanding hook and the upstanding arm where they leave the frame are twisted together, when the device is made of wire, which serves to give a rigid 65 and firm structure.

Having fully described my invention, what I claim as new and desire to secure by Letters Patent is:

1. A portière holder formed from a single 70 piece of wire bent to present a frame portion to support the body of the portière, the two ends of the wire bent upwardly from said frame, the shorter end being bent into the form of an upstanding hook adapted to 75 be inserted into the portière with its hooked end projecting to receive a suitable supporting device, the longer end being bent into the form of an arm extending well above said hook and formed above said hook into 80 a prong adapted to catch and support the upper edge of the portière.

2. A portière holder for French plaited heading portière formed from a single piece of wire bent to present a frame portion to 85 support the body of the portière, the two ends of the wire bent upwardly from said frame, the shorter end being bent into the form of an upstanding hook adapted to lie between the stitched plaits with its hooked 90 end projecting to receive a suitable supporting device, the longer end being bent into the form of an arm extending up parallel with and slightly separated from said hook and formed above said hook with a vertical 95 prong adapted to catch and support the upper edge of the portière.

3. A portière holder presenting a frame portion to support the body of the portière and provided with an upstanding hook 100 adapted to be inserted in the portière with its hooked end projecting to receive a suitable supporting device, and provided with an upstanding arm extending well above said hook and having a prong adapted to 105 catch and support the upper edge of the portière.

In testimony whereof, I have signed my name to this specification.

HELENE L. SWEENEY.
